APRON

Frances Collingwood, New York, N. Y.

Application April 26, 1950, Serial No. 9,487

Term of patent 7 years

(Cl. D3—26)

To all whom it may concern:

Be it known, that I, Frances Collingwood, a citizen of the United States, residing at New York, in the county and State of New York, have invented a new, original, and ornamental Design for an Apron, of which the following is a specification, reference being had to the accompanying drawing forming part thereof.

I claim:

The ornamental design for an apron, as shown.
FRANCES COLLINGWOOD.
